(57) **CLAIM**

The ornamental design for a fence pipe plumb level, as shown and described.

DESCRIPTION

FIG. 1 is a side elevation showing a first embodiment of our new design for a magnetic fence pipe plumb level, the opposite side being a mirror image thereof;

FIG. 2 is a top plan view thereof;

FIG. 3 is a bottom plan view thereof;

FIG. 4 is an end view thereof;

FIG. 5 is an end view opposite that shown in (FIG. 5);

FIG. 6 is a perspective view thereof;

FIG. 7 is a side elevation showing a second embodiment of our new design, the opposite side being a mirror image thereof;

FIG. 8 is a bottom plan view thereof;

FIG. 9 is a top plan view thereof;

FIG. 10 is an end view thereof;

FIG. 11 is an end view opposite that shown in (FIG. 10); and,

FIG. 12 is a perspective view thereof.

The article includes a symbolic break in a portion of the article. The appearance of the article between the break lines forms no part of the claimed design. The broken lines showing portions of the article form no part of the claimed design.

1 Claim, 2 Drawing Sheets
